US00D956742S

(12) **United States Design Patent** (10) Patent No.: **US D956,742 S**
Choi et al. (45) Date of Patent: **** Jul. 5, 2022**

(54) **PORTABLE ELECTRONIC DEVICE**

- (71) Applicant: **Samsung Electronics Co., Ltd.**, Suwon-si (KR)
- (72) Inventors: **Kwangha Choi**, Seoul (KR); **Sanhui Oh**, Seoul (KR); **Yongseok Bang**, Yongin-si (KR); **Jaehyung Hong**, Seoul (KR)
- (73) Assignee: **SAMSUNG ELECTRONICS CO., LTD.**, Suwon-si (KR)
- (**) Term: **15 Years**
- (21) Appl. No.: **29/645,212**
- (22) Filed: **Apr. 24, 2018**

Related U.S. Application Data

- (63) Continuation of application No. 29/582,594, filed on Oct. 28, 2016, now Pat. No. Des. 817,953.

Primary Examiner — Joseph Kukella*(74) Attorney, Agent, or Firm* — McAndrews Held & Malloy, Ltd.(57) **CLAIM**

The ornamental design for a portable electronic device, as shown and described.

DESCRIPTION

FIG. 1 is a front perspective view of a portable electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

In the drawings, the unshaded surfaces of the vertical sides, and the subject matter in broken lines, depict portions of the portable electronic device that form no part of the claimed design.
